UNITED STATES PATENT OFFICE.

FREDERICK G. GRUEN, OF CINCINNATI, OHIO, ASSIGNOR TO THE D. GRUEN SONS & COMPANY, OF CINCINNATI, OHIO, A CORPORATION OF OHIO.

DESIGN FOR A WATCH-BOW.

59,741.

Specification for Design.

Patented Nov. 22, 1921.

Application filed May 25, 1921. Serial No. 472,598. Term of patent 14 years.

To all whom it may concern:

Be it known that I, FREDERICK G. GRUEN, a citizen of the United States of America, and a resident of Cincinnati, in the county of Hamilton and State of Ohio, have invented a new, original, and ornamental Design for a Watch-Bow, of which the following is a specification, reference being had to the

accompanying drawing, forming part thereof.

The figure is a plan view of a watch bow embodying my invention.

I claim:

The ornamental design for a watch bow as shown.

FREDERICK G. GRUEN.
